COMBINED ELECTRIC FAN AND HEATER

Lee B. Green, Lakewood, Ohio

Application January 20, 1944, Serial No. 518,933

5 Claims. (Cl. 219—39)

This invention relates to electric fans and aims to provide an improved device of this kind which is very compact and in which the fan and motor unit is encased in a streamlined housing.

Another object of the invention is to provide an electric fan of this character having an electric heater therein for heating the air being delivered.

A further object of the invention is to provide an improved electric fan of the character mentioned, having novel oscillating mechanism therein.

Still another object of this invention is to provide an improved electric fan and heater of the character referred to, having novel means for controlling the operation of the fan and the operation of the electric heater.

The invention can be further briefly summarized as consisting of certain novel combinations and arrangements of parts hereinafter described and particularly set out in the appended claims.

In the accompanying sheets of drawings,

Fig. 1 is a longitudinal sectional view taken through a combined electric fan and heater embodying my invention;

Fig. 2 is a transverse sectional view taken through the device as indicated by line 2—2 of Fig. 1;

Fig. 3 is a partial sectional plan view taken on line 3—3 of Fig. 1 and showing linkage which forms a part of the oscillating mechanism;

Fig. 4 is an end view of the electric heating means showing the same in detached relation;

Fig. 5 is a partial perspective view further illustrating the construction of the electric heater;

Fig. 6 is a sectional plan view taken through the oscillating mechanism as indicated by line 6—6 of Fig. 2;

Fig. 7 is a vertical sectional view taken through the oscillating mechanism as indicated by line 7—7 of Fig. 6;

Fig. 8 is a transverse sectional view taken through the housing at a point adjacent the fan and heater control means as indicated by line 8—8 of Fig. 1;

Fig. 9 is a face view of the stationary switch member showing the same in detached relation, and

Fig. 10 is a diagram illustrating the electrical connections by which the motor and heating means are connected with the stationary switch member, the latter being shown in cross section as indicated by line 10—10 of Fig. 9.

Proceeding with a more detailed description of the present embodiment of my combined elec-

tric fan and heater, it will be seen from the drawings that the device comprises in general a casting or housing 12 connected with a support 13 and containing an electric heater 14 and a fan and motor unit 15 which operates to cause a stream of air to pass through the heater 14 and to be delivered from the housing. The device also embodies an oscillating mechanism 16 which is actuated from the fan and motor unit 15 and imparts oscillating movement to the housing 12. A control means for the device includes a switch knob or actuator 17 which is movable to control the supply of current to the heater 14 and the unit 15 and a control member or knob 18 for controlling the oscillating mechanism 16.

The housing 12 comprises a hollow sheet metal structure which in this instance is of a streamlined or bullet-like shape having a substantially cylindrical end portion 12a and a rounded or tapered end portion 12b which converges toward a transverse back or end wall 19. The converging end portion 12b of the housing is provided with a series of annularly spaced slots or openings 21 through which air enters the housing during operation of the fan and motor unit 15. The substantially cylindrical end portion 12a of the housing is the air delivery end of the device and is provided with a relatively reduced ring or flange portion 22 to which a substantially cylindrical extension or housing section 23 may be connected by means of suitably spaced screws 24. The housing section 23 contains the electric heating means 14 and locates the same in front of the fan and motor unit 15 so that air moved by the latter will be discharged through the heating element and delivered from the casing through the end opening 25 of the housing section 23. A guard 26, which in this instance is in the form of a spirally wound wire, is retained in the front opening 25 of the housing section 23 and prevents accidental contact with the electric heater 14.

The support 13 is here shown as comprising a base or standard 28 having an upstanding lug 29 to which a forked bracket 30 is rockably connected by the pin 31. The forked bracket 30 has an upstanding stem or post 32 connected therewith and on which the housing 12 is mounted by means of a sleeve 33 which surrounds the post. The sleeve 33 extends into the housing 12 in a transverse direction and has its outer or lower end suitably anchored or connected with the wall of the housing. The post 32 and the sleeve 33 cooperate to form a pivotal mounting for the housing 12 which will permit the latter to be

oscillated or swung laterally in a horizontal plane. The forked bracket 30 cooperating with the lug 29 forms a pivotal connection by which the housing 12 can be rocked or tilted for varying the inclination of the housing and the air stream in the vertical plane.

To facilitate lifting the device and tilting the housing 12 thereof on the pivot 31, I may provide the housing with a longitudinally extending elongated projection or handle member 35 which in this instance conforms to the curvature of the housing and is mounted on the upper portion thereof by means of the screw 36 and the interfitting lug 35a. The handle member 35 may be molded or otherwise formed, preferably of a material which does not readily conduct heat or electricity such as a suitable plastic.

It will be noted also in connection with the mounting of the device that the support 13 is connected with the housing 12 at an intermediate point of the latter and the fan and motor unit 15 is located in the housing so that the center of gravity of this unit will lie substantially on the extended axis of the post 32. This provides for a good balance being obtained in the device and contributes to quiet operation by reducing the tendency toward vibration.

The fan and motor unit 15 comprises an electric motor 38 which may be of any appropriate design or construction and a suitable fan or air impeller 39 which is mounted on the rotary shaft 40 of the motor. The frame of the motor may be provided with a plurality of projections or bracket elements 41 adapted to be connected with the housing 12 for mounting the unit 15 therein. The motor 38 drives the fan 39 in a direction to cause air to be drawn into the housing through the openings 21 and to be delivered from the housing in a stream after passing through the electric heater 14.

The electric heater 14 may comprise a plurality of coaxially disposed insulating rings 43 made of a suitable refractory material such as porcelain and a grid or element 44 formed of resistance wire and supported by such rings. As shown in the drawings the rings 43 are provided with cooperating annular grooves and circumferentially spaced axial lugs 45 and 46 permitting the rings to have an interfitting engagement by which they are held in the desired coaxial alignment and which permits the resistance wire 44 to be supported by the lugs 46, so that adjacent portions of such wire extend in spaced substantially parallel relation to each other.

The heater 14 is mounted in the housing section 23 by providing the latter with circumferentially spaced clips 47 having resilient arms 47a which grip the rings 43 and hold the same in the desired grouped and interfitting relation. The rings 43 are also provided with circumferentially spaced external radial lugs 49 which project outwardly and engage the wall of the housing section 23 for supporting and centralizing the heater 14 therein. If desired a layer or sleeve 49 of asbestos paper or other heat insulating material can be interposed between the heater 14 and the wall of the housing section 23.

The oscillating mechanism 16 will be described next. This mechanism includes a housing 51 which is suitably connected with the fan and motor unit 15, as by means of the screws 52, and contains gearing which is driven by the electric motor 38. The oscillating mechanism also includes linkage by which the fan and motor unit

are connected with the post 32 of the support 13, as will be presently described. The gearing contained in the housing 51 comprises worms 53 and 54 and worm gears 55 and 56 meshing respectively with such worms. The housing 51 is preferably constructed so that it will retain a quantity of lubricant in surrounding relation to the gearing therein.

The worm 53 is carried by an extension 57 of the motor shaft 40 which projects into the housing 51. The worm 54 is carried by a countershaft 58 which extends transversely of the housing 51 and with which the gear 55 is also connected. The worm gear 56 is connected with a vertical shaft 59 which extends through and is rotatably mounted in the top and bottom walls of the housing 51. The portion of the shaft 59 which projects through the lower wall of the housing 51 carries a crank 60 which extends through an opening or bushing 61 provided in the link 52.

With the arrangement of gearing just described, it will be seen that during operation of the fan and motor unit 15 the shaft extension 57 will rotate the worm 53 continuously. The worm 53 cooperating with the worm gear 55 will likewise drive the countershaft 58 and the worm 54 continuously. The worm gear 56 is shown in Figs. 6 and 7 in full lines and in mesh with the worm 54 at which time the gear 56 will also be driven and will cause rotation of the shaft 59 and the crank 60 carried thereby. Such rotation of the shaft 59 will cause pushing and pulling forces to be applied to the link 62 and the latter, being connected with the post 32, will cause an oscillating movement to be imparted to the housing 12.

For controlling the oscillating mechanism so as to permit the same to be rendered ineffective, the worm gear 56 is adapted to be moved or pulled out of mesh with its worm 54. Fig. 7 shows a dotted line position for the worm gear 56 in which the latter has been moved out of mesh with the worm 54. To permit such movement of the worm gear 56 into and out of mesh with the worm 54, I provide for axial movement of the shaft 59 and provide the latter with a thrust collar 64 with which a shifter arm or lever 65 cooperates. The arm 65 is carried by a control shaft 66 which projects through the rear wall of the housing 51 and extends rearwardly in the main housing 12 substantially coaxially with the motor shaft 40 and motor shaft extension 57. The outer end of the arm 65 is preferably provided with a hook portion 65a which loosely embraces the sleeve of the thrust collar 64 and is bent or curved so that its engagement with the thrust collar will be a substantially rocking or rolling contact. It should be mentioned at this point that the pin 60 of the crank 60 is of a length to permit the above mentioned axial shifting of the shaft 59 without being withdrawn from the bushing 61 of the link 60.

I have stated above that the link 62 of the oscillating mechanism is connected with the post 32 of the support 13. This is illustrated more fully in Figs. 1 and 3 of the drawings from which it will be seen that the link 62 has a forked end 62a which is pivotally connected with an anchor link 68. The anchor link 68 has a ring or washer portion 68a which is mounted on the upper end of the post 32 and retained thereon by the nut 69. The link 68 is held against rotation relative to the post 32 by means of cooperating flat faces 70 provided on these parts.

The control means referred to above as including the selectively operable control members 17 and 18 will be described next. The control member or actuator is in the form of a disk or ring and constitutes a part of an electric switch for controlling the operation of the motor 38 and the supply of current to the electric heater 14. The actuator 17 carries a movable switch member 72 which cooperates with contacts of a stationary switch member 73. This stationary switch member comprises an insulating body or plate which is suitably connected with the transverse wall 19 of the housing 12 and carries an arcuately extending row of stationary contacts 74 which are located opposite an arcuate opening 75 of such transverse wall so that they will be engaged by the movable switch member 72.

As will be seen from the diagram shown in Fig. 10, the two contacts designated 74a are connected with the current supply conductor 76. The two contacts 74b and 74c are both connected with the motor 38. The single contact 74d, which is offset with respect to the arcuate row formed by the other stationary contacts, is connected with the heating element 14. As shown in Fig. 8 the movable switch member 72 has a bowed body portion 72a which cooperates with and spans certain of the stationary contacts 74a, 74b and 74c during movement of such switch member to its different positions. This switch member also has an arm portion 72b which cooperates with the offset stationary contact 74d.

The switch member 72 is movable to three different positions which are represented diagrammatically in Fig. 9 by the lines 77, 78 and 79. When the switch member 72 is in position represented by the line 77 the contact 74b for the motor 38 is connected with one of the current supply contacts 74a. This will result in operation of the fan and motor unit without energization of the electric heater 14 so that unheated air will be delivered by the device when this is desired. When the switch member 72 is moved to the off position represented by the line 78, the switch member is then in engagement with the two contacts 74a but does not engage any of the other contacts and hence neither the motor nor the heater are energized at this time. When the switch member is moved to the position represented by the line 79, the body portion 72a connects one of the contacts 74a with the contact 74c so that current will then be supplied to the heater 14. At this time the arm 72b also engages the motor contact 74d so that current will also be supplied to operate the motor 38. Thus whenever the switch is moved to the position 79 to energize the heater 14, current is necessarily also supplied to the motor 38 so that air will be delivered through the heating element and will prevent overheating of this element and of the casing portions adjacent thereto.

From Figs. 1 and 8 it will be seen that the movable switch member 72 projects through the arcuate opening 75 of the transverse wall 19 so as to engage and cooperate with the contacts 74 of the stationary switch member 73 in the manner just explained above. For limiting the movement of the switch member 72 during the shifting thereof to the end positions 77 and 79, I provide the actuator 17 with axial projections 80 which extend through the arcuate opening 75 and serve as stops which engage the ends 75a of this arcuate opening.

The shaft 66 for controlling the oscillating mechanism 16 extends rearwardly substantially

coaxially of the housing 12, as mentioned above, and is connected with the control knob 18. By rotating the control knob 18 rocking movement is imparted to the arm 65 in the housing 51 for shifting the worm gear 56 into and out of mesh with the worm 54 as explained above. The knob 18 also serves as a means for retaining the switch actuator 17 in its operative position adjacent the transverse wall 19 of the housing 12.

10 To enable the control knob 18 to accomplish these functions, I provide the shaft 66 with a sleeve or enlargement 82 adjacent its outer end which projects through and is supported in a central opening of the transverse wall 19. This 15 sleeve is suitably connected with the shaft 66 as by means of welding indicated at 83. The sleeve 82 extends through the control member 17 and forms a supporting shaft for the latter. A screw 84 extending into the outer end of the sleeve 82 retains the control knob 18 on such sleeve. The control knob 18 is prevented from rotating relative to the sleeve 82 by making the stem portion 82a of non circular cross section and providing the knob 18 with a correspondingly shaped opening therein. A spring 85 attached to the inner end of the sleeve 82 serves as a detent which cooperates with the notches 86 of the wall 19 for releasably holding the shifter arm 65 in its different positions corresponding with the effective and ineffective settings of the oscillating mechanism.

As will be seen from Fig. 1, the taper provided on the housing 12 imparts to the latter a desired attractive and streamlined shape. By constructing the control members 17 and 18 with a bevel or taper corresponding with the taper of the housing 12 they will complete the desired streamline or bullet shape of the latter.

From the foregoing description and accompanying drawings it will now be readily seen that I have provided a novel form of combined electric fan and heater which is very compact in construction and of an attractive and streamlined shape. It will be seen also that this device embodies novel oscillating mechanism which can be economically produced and which will afford smooth and quiet operation. It will now also be evident that the novel control means embodied in my oscillating heater fan will enable the same to operate in a safe and efficient manner.

50 While I have illustrated and described my combined electric fan and heater in considerable detail, it will be understood of course that I do not wish to be correspondingly limited but regard my invention as including all changes and modifications coming within the spirit of the invention and the scope of the appended claims.

Having thus described my invention, I claim:

1. An electric fan comprising an elongated housing open at one end thereof and at its other end having an air inlet opening, an electric heating element located in said housing and extending transversely thereof adjacent said open end, a support connected with said housing at an intermediate point thereof for supporting the device, and a fan and motor unit mounted in said housing with its center of gravity lying substantially in a transverse plane which extends through the axis of said support and being operable to cause a stream of air to be drawn into 60 the housing through said inlet opening and discharged from the housing across said heating element and through said open end, said unit being spaced from the wall of said housing so as to be substantially surrounded by an air passage connecting said inlet opening with said open end and

through which said stream flows around and in cooling contact with said unit before reaching said heating element.

2. In an electric fan, an elongated housing having air inlet and delivery openings adjacent its opposite ends, a sleeve connected with the wall of said housing and extending into the housing in a transverse direction and at an intermediate point thereof, a support having a stem extending into said sleeve for mounting the device for oscillation, a fan and motor unit mounted in the housing between said inlet and delivery openings and directly over said support and with its center of gravity lying substantially in a transverse plane extending through the axis of said support, an electric heating element located in the housing adjacent the delivery opening thereof, and oscillating mechanism located in the housing and driven by said unit for oscillating the device, said fan and motor unit being spaced from the wall of said housing to provide a passage for a flow of air from the inlet opening to the delivery opening around and in cooling contact with the fan and motor unit before reaching said heating element and said fan and motor unit being operable to cause said flow of air through said passage.

3. An electric fan comprising an elongated housing open at one end thereof and at its other end having a bullet-shaped nose provided with air inlet openings, an electric heating element located in said housing and extending transversely thereof adjacent said open end, a support connected with said housing at an intermediate point thereof and supporting the device for oscillating movement, a motor and fan unit mounted in said housing directly over said support and with its center of gravity lying substantially in a transverse plane extending through the axis of said support and being operable to deliver a stream of air across said heating element and through said open end, said unit being spaced from the wall of said housing so as to be substantially surrounded by an air passage connecting the air inlet openings with said open end and through which said stream flows around and in cooling contact with said unit before reaching said heat-

ing element, and oscillating mechanism located entirely within said housing and driven by said unit and including linkage operably connected with said support.

4. An electric fan comprising an elongated housing open at one end and convergently tapered at the other end, said tapered end having an air inlet opening therein, an electric heating element in said housing adjacent said open end, a support connected with the housing at an intermediate point thereof and mounting the device for oscillating movement, a fan and motor unit mounted in said housing between said air inlet opening and said heating element and directly over said support and operable to deliver a stream of air through said open end, an oscillating mechanism carried by said unit and operable to impart oscillating movement to the device, a control shaft projecting from said mechanism and extending substantially coaxially of said convergently tapered end, and a knob on said shaft conforming with the convergent taper of said housing.

5. An electric fan comprising an elongated housing open at one end and convergently tapered at the other end, said tapered end having an air inlet opening therein, an electric heating element in said housing adjacent said open end, a support connected with the housing at an intermediate point thereof and mounting the device for oscillating movement, a fan and motor unit mounted in said housing between said air inlet opening and said heating element and directly over said support and operable to deliver a stream of air through said open end, a switch controlling said fan and motor unit, an oscillating mechanism carried by said unit and operable to impart oscillating movement to the device, a control shaft projecting from said mechanism, and extending substantially coaxially of said convergently tapered end, a knob on the outer end of said shaft, and a switch actuating member between said knob and housing, said actuating member and knob conforming to the convergent taper of the housing.

LEE B. GREEN.
